UNITED STATES PATENT OFFICE.

FRANK C. URSPRUNG, OF NEW YORK, N. Y., ASSIGNEE TO UNDERWOOD TYPEWRITER COMPANY, OF NEW YORK, N. Y., A CORPORATION OF DELAWARE.

TYPE-WRITING MACHINE.

1,064,674.

Specification of Letters Patent. Patented June 10, 1913.

Application filed November 16, 1910. Serial No. 592,615.

To all whom it may concern:

Be it known that I, FRANK C. URSPRUNG, a citizen of the United States, residing in New York, in the county of New York and

5 State of New York, have invented certain new and useful Improvements in Type-Writing Machines, of which the following is a specification.

This invention relates to center guides for 10 type bars, such guides being usually fixed upon the framework of the machine at the vicinity of the printing point, and a machine usually having a single center guide, although in some cases more are provided.

15 The invention is shown as applied to an Underwood front strike writing machine, which is usually constructed with a fixed guide-fork for the type bars, said guide-fork arranged just below the printing point, and constructed to receive guide bits or 20 projections which are formed on the type bars just below the type heads. By means of this forked guide, lateral play of the types is prevented.

25 In order to prevent vertical play of the types, or to insure that the types shall register vertically as well as horizontally, I provide an auxiliary guide, which may be located between the forks of the usual fixed 30 guide, and preferably engages said projections on the type bars. One of the co-operating type-bar guiding members is recessed, and the other has a projection which fits in the recess, to secure accuracy of vertical alinement.

35 One of the principal features of the invention consists in mounting such an auxiliary guide so that it will yield, and hence not prevent the types from striking the 40 platen or the paper thereon, nor cause the types to stick to the guide. A V-notch is formed preferably on the type bar, and the yielding guide has a projection of corresponding form. These parts fit or wedge 45 together as the type approaches the platen; this action of the auxiliary guide being sufficient in practice to assure accuracy of vertical alinement.

50 While the invention shows fixed guides for sidewise alinement, and a yielding guide for vertical alinement, still it will be understood that the yielding feature is applicable to other than vertical guides for the types; and it will also be understood that the 55 yielding guide may be employed whether or

not in connection with a fixed guide or guides.

Other objects and advantages will hereinafter appear.

In the accompanying drawings, Figure 1 60 is a perspective, partly broken away, showing the invention applied to an Underwood writing machine. Fig. 2. is a side view, showing a type bar engaging the center guide. Fig. 3 shows the centering notch fitting the guide at the moment when the type strikes the platen. Fig. 4 is a side view, of the invention, this view showing an Underwood writing machine in central vertical section. Fig. 5 is a detail front view of the 70 type guide.

Types 1 are mounted on the heads 2 of type bars 3 fulcrumed on a rod 4 in radial slots 6 of a segment 5 fast to the framework 7 of the machine. Depression of a key 8 75 causes a lever 9 to rock an elbow lever 10, the latter connected to one end 11 of the type bar 3 to swing the latter upwardly and rearwardly against a platen 12. Said platen is fixed to an axle 13, mounted in carriage 80 14 which travels on the front and rear rails 15, 16. As the free end of the type bar 3 approaches the platen, its upper portion enters between converging fixed guide fingers or forks 17 projecting forwardly from arms 85 18 of a type bar guide mounted on the frame 7, said fingers preventing lateral shake of the type bars. Each of the type bars has a guide-bit or tongue 19, fitting between the forks 17, and provided with a tapering centering notch 20. As the bit enters between the forks 17, said notch becomes a seat for a pointed projection or gage 21, mounted on a stem 22, which is placed between the arms 18, of the usual type guide, in line with 90 and slightly below the printing point. One or both of the diverging walls of the notch 20 engages the projecting point 23 of the gage; and as the type bar continues to press toward the platen, it is caused to shift 100 bodily upwardly or downwardly, relatively to its fulcrum 4, (depending upon whether the lower or the upper wall of the notch strikes the gage) until the notch is centered relatively to and fits over the point of the 105 gage (Fig. 3) at which time, the type is in direct alinement with the printing line, and is held against vertical displacement.

The stem 22 is preferably pivoted to enable it to yield. For this purpose it is 110

mounted on any suitable support, as for instance on the usual connecting screw 24 between the arms 18, the gage being held forward of the platen by a spring 25. This spring 25, although weak, is sufficient to hold the gage stationary or nearly so while the notch of the type bar is fitting itself to the gage. The bar then rocks the gage idly back until the type strikes the platen 10 through a ribbon 26, the type being guided by said gage as it recedes. Each type will be guided by the gage to the same horizontal printing line on the sheet because the centering notches 20 are each located the same 15 distance from the centers of said type characters. Upon releasing the key 8, the type bar 3 returns to its idle position, (Fig. 4,) it being assisted thereto by the spring 25, which returns the gage 21 to normal position 20 (Figs. 1 and 4).

The yielding action of the type guide enables it to come to a fit with the type bar without preventing the type from printing, and without causing the type bar to stick to 25 the guide. The invention is especially of value where the type bars are liable to wear and become loose upon their pivots; and it is also of value for the side type bars of the machine, which are liable to spring or shake 30 up and down unless a center guide is provided to prevent it.

The point of my gage is approximately a right angle, so that it is impossible for it to lock with any type bar, and also it will bring 35 the type to proper alinement, even though the type tends to swing far out of line. The gage normally lies within the fixed guide fingers, so that it will not interfere with placing any thickness of work in the machine, and since it swings, it will also just 40 as effectively aline, and permit printing on the thinnest sheets.

It will be understood that the invention is of value whether used with or without 45 fixed center guides, and also usable for guiding the bars otherwise than vertically when required.

Having thus described my invention, I claim:

50. 1. In a typewriting machine, the combination with a platen, and type bars having types, of a yielding centering guide and fixed side guide fingers, engaged by the bars as the types approach the platen, to aline 55 said types.
2. In a typewriting machine, the combination with a platen and type bars having types, of a gage in the path of the type bars to aline the types, said gage being movable 60 to accommodate different thicknesses of

work sheets, fixed side guide fingers, and means to hold the gage normally advanced from the platen.

3. In a typewriting machine, the combination with a platen, and type bars having 65 types, of a spring-returned centering guide engaged by the bars as the types approach the platen, and fixed side guide fingers, to aline the types with the printing line and to steady the type bars at the time of impact 70 against the platen.

4. In a typewriting machine, the combination with a platen, type bars having types and a type bar guide, of a centering guide pivoted between the arms of the type bar 75 guide, a spring to hold the centering guide advanced from the platen, said type bars each having a centering notch to fit over the centering guide, as its type approaches the platen to direct the types to the printing 80 line.

5. In a typewriting machine, the combination with a platen, of type bars having centering notches extending across said bars, types on the bars, fixed side guide fingers, a 85 yielding centering guide in the path of the type bars, comprising a tapering gage over which the notches fit to shift the type bars bodily relatively to their fulcrums, and direct the types to the printing line. 90

6. In a typewriting machine, the combination with a platen, of type bars, a centering gage lying in the path of the bars, said bars each having a centering notch to fit over the gage, which notch is cut across the width 95 of the bar, to enable the bar to readily free itself from the gage.

7. In a typewriting machine, the combination with a platen, of type bars, a yielding centering gage lying in the path of the type 100 bars, said bars each having a centering notch to fit over the gage, which notch is cut across the width of the bar, to enable the bar to readily free itself from the gage, and means to return the gage to normal position after the impact of the types against the platen. 105

8. In a typewriting machine, the combination with a platen and a type bar having a type to strike the platen, of a fixed guide 110 finger, a gage pivoted on said finger, a spring holding said gage away from the platen, and a part on the type bar co-operating with said gage to aline the type as it moves toward the platen.
